(57) **CLAIM**

The ornamental design for a check valve part for automobile as shown and described.

DESCRIPTION

FIG. 1 is a perspective view of a check valve part for automobile showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is a perspective view thereof, shown in an in-use condition.
The dash-dot lines in FIG. 3 are the boundary lines that form no part of the claimed design. The evenly spaced broken lines in the drawings illustrate portions of the check valve part for automobile that form no part of the claimed design.

1 Claim, 9 Drawing Sheets
